LADY'S COMB

Siegfried Behr, Flushing, N. Y.

Application September 6, 1955, Serial No. 37,788

Term of patent 7 years

(Cl. D86—8)

Fig. 1 is a top plan view of a lady's comb, showing my new design.

Fig. 2 is a front elevational view thereof.

I claim:

The ornamental design for a lady's comb, as shown.
